UNITED STATES PATENT OFFICE.

EMORY GLENN SIMPSON, OF DETROIT, MICHIGAN, ASSIGNOR TO FISHER BODY CORPORATION, OF DETROIT, MICHIGAN, A CORPORATION OF NEW YORK.

DOOR OPENER.

Application filed December 15, 1922. Serial No. 607,115.

To all whom it may concern:

Be it known that I, EMORY GLENN SIMPSON, citizen of the United States, residing at Detroit, in the county of Wayne and State of Michigan, have invented certain new and useful Improvements in Door Openers, of which the following is a specification.

This invention relates to door openers and has for its object a device calculated to throw the door partially open as the latch is released. In the doors now used in automobile body construction it is customary to use some form of a gripping device to hold the door securely to the door post so as to prevent vibration and rattling; one of the devices common in use in closed body construction is made under the O'Brien Patent No. 1,098,393, June 2, 1914. This device is called commercially a dove-tail. It is very effective for securely holding the door and preventing rattling, but it causes the door to stick when an effort is made to open it due to the heavy pressure under which the striker on the door is gripped. It is the object of the present invention to store energy when the door is closed, which energy is released when the latch is retracted and used to throw the door open so as to avoid the effort otherwise necessary to disengage the door from the gripping device. Furthermore, the door may stick for other reasons, such as the fit of the hinges or the fit in the door opening.

In the drawings:

Fig. 1 is an inside elevation of a fragmentary body construction showing in dotted lines the latch, the door gripping device, and the door opener.

Fig. 2 is a vertical section through the door gripping device.

Fig. 3 is a section on the line 3-3 of Fig. 2.

Fig. 4 is a fragmentary vertical section of a modified form of door gripping device and door opener taken on the line 4-4 of Fig. 5.

Fig. 5 is a cross section of the same.

Fig. 6 is a section taken on the line 6-6 of Fig. 5.

Fig. 7 is a perspective of the rubber block in the gripping device.

Fig. 8 is a perspective of the wear member of cup.

Referring to Figs. 1 to 3 inclusive,

represents an ordinary door latch now in common use. This is secured to the door *b* while the keeper *c* is secured to the door post *d*. There is ordinarily used in connection with the latch, a gripping device designated *e* which is commonly called a "dove-tail" and which is provided with a striker *f*. This gripping device or dove-tail is detailed in Figs. 2 and 3 and comprises a casing *g* provided with upper and lower chambers *h* and *i*. It has been customary to fill both of these chambers with rubber blocks *j*, however, in the lower chamber *i* I mount a spiral spring *k* which has a spring arm *m* adapted to engage with the nose of the striker *f* and put under strain when the striker travels between the stationary wear plate *n* and the movable wear plate *o*. The movable wear plate is slightly raised and the rubber block *j* distorted and consequently securely grips the striker *f*. This holds the door from rattling.

When the door latch is released the spring arm *m* exercises a force of substantially 40 lbs. against the nose of the striker and forces it out between the wear members and causes the door to open clear of the door opening; this enables the door to be easily pushed open.

In Figs. 4 to 8 inclusive I have shown a modified form in which the dove tail is constructed precisely as has been heretofore the custom but the spiral spring *x* is secured by clip *y* to an angle plate *v* riveted to the back of the casing *g*. The spiral spring has an arm *p* adapted to engage the striker *f* and be put under strain. When the latch is released the arm *p* throws to the dotted line position shown in Fig. 5 thereby disengaging the striker between the movable wear plates *o*.

What I claim is:

1. In a dovetail device, the combination of a casing, resilient means in the casing, a pair of wear members, a striker adapted to be secured to the door for entering between the wear members and separating them against the resistance of the yielding members, and a spring operating independently of said "dovetail" and supported adjacent by said casing said spring operating between the wear members and put under strain by the striker engaging the same when the door closes, whereby when the door latch is released the spring will throw the striker

member clear of the wear members and partially open the door.

2. In a "dove-tail" member, the combination of a casing, a yieldable member in the casing exerting pressure, wear plates engaged by said member, a striker passing between the wear plates for spreading the same, and a spiral spring operating independently of said "dovetail" and having one arm in the path of the striker between the wear plates for exerting pressure against the striker to release the same from the wear plates when the door latch is released.

3. In a dove-tail, the combination of a casing adapted to be carried by the door post having a rubber block and wear plates, a striker adapted to be supported by the door and adapted to drive in between the wear plates to spread them against the resistance of the blocks, and a spring supported by the casing and operating independently of the "dovetail," said spring

adapted to be put under strain by the striker when the same travels between the wear plates, whereby when the door latch is released such spring exerts sufficient energy against the striker to throw the same clear of the wear plates and partially open the door when the latch is released.

4. In a dove-tail device, the combination of a casing, a resilient means in the casing, a pair of wear members acted upon by the resilient means, a striker adapted to be secured to the door for entering between the wear members and for separating them against the resistance of the yielding members, and independent means engaged by said striker for storing energy to throw the striker from its engagement with the wear members when the door latch is released.

In testimony whereof I affix my signature.

EMORY GLENN SIMPSON.
